UNITED STATES PATENT OFFICE.

OTTO SIEGLER AND EUGENE SIEGLER, OF BELLEVILLE, ILLINOIS, ASSIGNORS TO SIEGLER ENAMEL RANGE COMPANY, OF BELLEVILLE, ILLINOIS, A CORPORATION OF ILLINOIS.

OVEN BAFFLE PLATE WITH ATTACHED BURNER FOR COMBINATION COAL AND GAS RANGES.

Application filed March 14, 1924. Serial No. 699,204.

To all whom it may concern:

Be it known that we, OTTO SIEGLER and EUGENE SIEGLER, citizens of the United States, residing in the city of Belleville,

5 county of St. Clair, and State of Illinois, have invented a certain new and useful Improvement in Oven Baffle Plates with Attached Burners for Combination Coal and Gas Ranges, of which the following is a 10 full, clear, and exact description, such as will enable others skilled in the art to which it appertains to make and use the same.

This invention relates to combination coal and gas ranges, and particularly, to the 15 oven burners of such stoves.

In stoves of the type referred to it is the usual practice to heat the oven with a gas burner attached to a baffle plate which is removably mounted in the oven. Prior to 20 our invention it was the usual practice to equip the oven burner of a combination coal and gas range with the two rows of orifices or gas ports disposed on the underside of the burner so as to cause jets of gas to be 25 projected downwardly against the bottom of the oven, and provide the baffle plate with a heat insulated central portion surrounded by a perforated portion up through which the heat from the bottom of the oven as 30 cends. This method of heating the oven of a combination coal and gas range has not proved entirely satisfactory, owing to the uneven distribution of the heat and to the relatively long time required to heat the 35 oven.

The main object of our invention is to provide a removable baffle, with attached burner, for the oven of a combination coal and gas range which is constructed in such 40 a way that the heat will be distributed practically uniformly through the entire area of the oven.

Another object is to provide an oven burner for a combination coal and gas range 45 that will not only heat an oven quicker, but with the consumption of less gas than the oven burners heretofore used in combination coal and gas ranges.

And still another object is to provide a 50 combined baffle plate and gas burner for the purpose described that is inexpensive to manufacture.

Figure 1 of the drawings is a perspective view of a portion of a combination coal and gas range embodying our invention.

Figure 2 is a top plan view of the baffle plate.

Figure 3 is a bottom plan view of the baffle plate, showing the burner attached to same; and

Figure 4 is a transverse sectional view, taken on the line 4—4 of Figure 2.

Referring to the drawings which illustrate the preferred form of our invention, A designates the oven of a combination coal and gas range, B designates as an entirety 65 a baffle plate that is removably mounted in said oven, and C designates a gas burner that is attached to the underside of said baffle plate. The baffle plate B is of rectangular shape in general outline and is provided at its side edges with laterally-projecting arms 1 equipped with depending portions 2 that rest upon flanges 3 or other suitable supports on the side walls of the 70 oven. The laterally-projecting arms 1 hold the side edges of the baffle plate in spaced relation with the side walls of the oven A, and thus form passageways x at the sides of the baffle plate up through which the 75 heat ascends from the bottom portion of the oven. Said baffle plate is also provided at its rear end with arms 4 that hold the rear end of the baffle plate in spaced relation with the rear wall of the oven, and thus 80 form a passageway similar to the passageways x previously referred to up through which the heat from the lower portion of the oven ascends. If desired, the baffle plate can be provided at its front end with forwardly-projecting arms 5 that hold the 85 front end of the baffle plate in spaced relation with the door of the oven, so as to form a passageway similar to the passageways x.

The gas burner C on the underside of the baffle plate B preferably consists of a continuous burner that extends around the four sides of the oven, and the gas jets or orifices 6 in said burner are arranged on the upper 100 side of same, as shown in Figure 4 and are so disposed that the jets of gas which emerge from the burner will be projected upwardly on the underside of the peripheral portion

7 of the baffle plate B, thereby causing the heat to be distributed practically uniformly throughout the entire area of the oven. The particular shape of the burner C is immaterial, but we prefer to make said burner of rectangular form in general outline so that it will have two side portions arranged adjacent the side walls of the oven, a rear portion arranged adjacent the back wall of the oven and a front portion arranged adjacent the door of the oven when said door is closed. Gas is supplied to the burner C through an intake portion 8 on said burner located at the rear end of same, and in order to insure the gas stream dividing and flowing uniformly through the portions of the burner which branch laterally from the intake portion 8, we arrange a deflector 9 in the burner adjacent the intake portion 8, as shown in Figure 3. In our improved baffle plate the central portion of same is not protected by asbestos or other heat insulating material, but, on the contrary, the central portion 10 of our baffle plate is constructed in such a way that heat will radiate upwardly from same, and thus supply heat to the central portion of the oven. While the particular construction of the baffle plate B is immaterial, so far as our broad idea is concerned, we have found that excellent results will be obtained if the peripheral portion 7 of the baffle plate is formed of cast metal and the central portion 10 of the baffle plate is formed of sheet metal, the cast metal peripheral portion imparting the required rigidity to the baffle plate and serving as an excellent deflector for the flames that emerge from the burner C, and the sheet metal central portion 10 of the baffle plate insuring the required amount of heat being supplied to the central portion of the oven. As shown in Figures 3 and 4, the peripheral portion 7 of the baffle plate is provided at its inner edge with inwardly-projecting lugs 11 to which the burner C is connected by bolts or other suitable fastening devices 12 that pass upwardly through supporting brackets 13 on the upper side of the burner C. The piece of sheet metal 50 from which the central portion 10 of the baffle plate is formed has its peripheral edge flanged downwardly at 14 so as to reinforce and strengthen same, and said plate is supported by the inwardly-projecting lugs 11 on the peripheral portion of the baffle plate and is retained in position by the fastening devices 12 that are used to secure the burner C to the baffle plate. For convenience in manufacturing it is preferable to construct the peripheral portion of the baffle plate from two identical castings of such form that when they are assembled they will cooperate with each other to form a rectangular-shaped member, as shown in Figure 2, said castings being detachably connected to-

gether by bolts or other suitable fastening devices 15. A combined baffle plate and oven burner of the construction above described insures an even distribution of the heat in the oven in which it is used, owing to the fact that the burner C is continuous, or in other words, extends around all four sides of the oven, and is provided on its upper side with gas jets or orifices which are so disposed that the flames which emerge from the burner will be projected upwardly against the underside of the peripheral portion of the baffle plate and in close proximity to the passageways at the sides, rear and front of the oven up through which the heat ascends. As the central portion of the baffle plate is not covered by heat insulating material, some heat will radiate upwardly from the central portion of the baffle plate, and thus supply heat to the central portion of the oven, and still another advantage of such a structure is that it consumes less gas than burners of the kind heretofore used in the ovens of combination gas and coal ranges.

Having thus described my invention, what I claim as new and desire to secure by Letters Patent is:

1. A baffle plate for the purpose described, consisting of a frame of rectangular shape in general outline provided with inwardly and outwardly extending projections, a member detachably connected to said inwardly extending projections so as to form the central portion of the plate, and a continuous burner on the underside of said plate connected to said inwardly extending projections and provided with gas orifices.

2. A device for heating the oven of a combination gas and coal range, comprising a baffle plate adapted to be arranged inside of the oven and composed of an unprotected sheet metal central portion and a cast metal peripheral portion that surrounds said central portion, and a gas burner on the underside of said plate conforming to the outline of said peripheral portion and provided with gas orifices disposed so that jets of gas will be projected outwardly and upwardly towards the vertical walls of the oven and against the underside of the peripheral portion of said baffle plate.

3. A device for heating the oven of a combination gas and coal range, comprising a baffle plate adapted to be arranged inside of the oven and composed of an unprotected sheet metal central portion and a cast metal peripheral portion that surrounds said central portion, a gas burner attached to the underside of said plate adjacent the inner edge of said peripheral portion and provided with gas orifices disposed so that jets of gas will be projected outwardly and upwardly towards the vertical walls of the oven and against the underside of the peripheral portion of said baffle plate, said

burner conforming in general outline to the shape of the peripheral portion of the baffle plate and being provided with an intake portion, and a deflector for causing the gas flowing through said intake portion to split up into two streams and flow through the burner.

4. A device for heating the oven of a combination coal and gas range, comprising
10 a baffle plate adapted to be arranged inside of the oven and provided with means that maintains the edges of said plate in spaced relation with the vertical walls of the oven so as to form passageways up through
15 which the heat ascends, said plate being composed of a cast metal peripheral portion of rectangular shape in outline and a central portion formed from a sheet metal plate, and a substantially rectangular-shaped gas
20 burner arranged on the underside of said plate at the inner edge of said peripheral portion and provided on its upper side with gas orifices disposed so that jets of gas will be projected outwardly and upwardly
25 against the underside of said peripheral portion of said baffle plate.

5. A baffle plate for the purpose described, consisting of a cast metal frame of rectangular shape in general outline provided at its sides and at its front and rear ends with laterally-projecting arms, in-

wardly-projecting lugs on the inner side of said frame, a piece of sheet metal secured to said lugs so as to form the central portion of the baffle plate and having its peripheral edge portion flanged downwardly, and a continuous gas burner on the underside of the baffle plate secured to said lugs and provided with gas orifices disposed so that jets of gas will be projected outwardly and upwardly against the underside of said frame.

6. A baffle plate for the purpose described, consisting of a cast metal frame of rectangular shape in general outline provided at its sides and at its front and rear ends with laterally-projecting arms, inwardly-projecting lugs on the inner side of said frame, a piece of sheet metal secured to said lugs so as to form the central portion of the baffle plate and having its peripheral edge portion flanged downwardly, a continuous gas burner on the underside of the baffle plate secured to said lugs and provided with gas orifices disposed so that jets of gas will be projected outwardly and upwardly against the underside of said frame, an intake portion on said gas burner, and a deflector for causing the gas flowing through said intake portion to divide into two streams and flow through the burner.

OTTO SIEGLER.
EUGENE SIEGLER.
